UNITED STATES PATENT OFFICE.

SAMUEL F. KLOHS, OF CHICAGO, ILLINOIS.

CAR-COUPING.

No. 814,379.

Specification of Letters Patent.

Patented March 8, 1908.

Application filed October 7, 1905. Serial No. 281,766.

To all whom it may concern:

Be it known that I, SAMUEL F. KLOHS, a citizen of the United States, residing at Chicago, in the county of Cook and State of Illinois, have invented certain new and useful Improvements in Car-Couplers; and I do hereby declare the following to be a full, clear, and exact description of the invention, such as will enable others skilled in the art to 10 which it appertains to make and use the same.

My invention relates to the draft-rigging and draft appliances of railway-cars, and particularly to the attachment of the spring 15 pocket or yoke to the rear end of a coupler-shank or draw-bar.

The usual construction of spring-pockets and couplers and their application to each other by means of two rivets does not afford 20 a sufficiently secure connection for such parts under the conditions of present and increasing weight of cars and trains, as the ends of the rivets frequently strip off or 25 slightly bend, thus permitting the yoke to spread and the coupler to pull out. By so forming and arranging the yoke and coupler-shank or draw-bar that the connecting devices therefor are in double shear the objections heretofore noted are entirely obviated, 30 and therefore my invention, generally stated, may be said to reside in a construction wherein the yoke and draw-bar are so formed that the bolts, rivets, or other fastening devices employed to connect them are in double shear.

There are other minor features of invention, all as will hereafter more fully appear.

In the drawings chosen for the purpose of illustrating my invention, the scope whereof 40 is pointed out in the claims, Figure 1 is a side elevation of a car-coupler and yoke or spring-pocket, showing a construction embodying my invention. Fig. 2 is a perspective view of the rear end of the coupler illustrated in 45 Fig. 1. Figs. 3 and 4 are perspective views showing modified forms of the rear end of the coupler.

Like symbols refer to like parts wherever they occur.

I will now proceed to describe my invention more fully, so that others skilled in the

art to which it appertains may apply the same.

In the drawings, 1 is a coupler-shank or draw-bar, the rear or inner end of which is provided with a plurality of slots or pockets 2, 55 that are adapted to receive the ends of a yoke or spring-pocket 3. The yoke or spring-pocket 3, which surrounds the usual followers, and draft-spring (not shown) or other 60 devices for a similar purpose may be of any suitable form, the ends 4, 4 thereof being adapted to be received in the pockets or slots 2, 2, with which the rear end of the coupler is provided. It will be noted that the construction is such that portions of the rear end 65 of the coupler-shank overlie the ends of the yoke and that a portion of said shank is interposed between the ends of the yoke, thereby affording support on both sides of the ends 70 of the yoke for the attaching-bolts and causing said bolts to be in double shear.

Bolts 5, which pass through the rear end of the coupler-shank and the ends of the yoke and which are each provided with a nut or a 75 cotter 6, are preferably employed to connect said yoke and coupler, as by reason of the said bolts being supported by the draw-bar in such manner that they are in double shear the connection between such parts is maintained with greater security than by the use 80 of rivets in the present manner, while the yoke and coupler are thus permitted to be readily separated when occasion requires.

Having thus described my invention, what I claim, and desire to secure by Letters Patent, is—

1. A car-coupler having slots adapted to receive a yoke or spring-pocket, said coupler on opposite sides of each slot being provided 90 with means adapted to support a yoke-fastening.

2. A car-coupler having its rear end provided with a portion adapted to be interposed between the ends of a yoke or spring-pocket and having a portion adapted to overlie an end of said yoke, and form a support 95 for a yoke-fastening.

3. A car-coupler having its rear end adapted to engage a yoke or spring-pocket and having portions adapted to overlie said yoke, and form a support for a yoke-fastening.

4. A car-coupler adapted to be connected to a yoke or spring-pocket by a suitable fastening, the shank of said coupler being provided with means for supporting said fastening in double shear.

5. The combination with a car-coupler, of a yoke or spring-pocket, and a suitable fastening in double shear connecting said coupler and yoke.

6. The combination with a car-coupler

having slots adapted to receive a yoke, a yoke or spring-pocket, and bolts connecting said coupler and yoke, said bolts being in double shear.

In testimony whereof I affix my signature ¹⁵ in presence of two subscribing witnesses.

SAMUEL F. KLOHS.
